PACKAGING TRAY FOR A FILM REEL

Harold Glazer, Kansas City, Mo., assignor to Crown-Bremson Industries, Inc., Kansas City, Mo., a corporation of Maryland

Filed Apr. 26, 1963, Ser. No. 74,628

Term of patent 14 years

(Cl. D58—12.6)

FIG. 1 is a top perspective view of a packaging tray for a film reel, showing my new design;

FIG. 2 is an elevational view of one side thereof;

FIG. 3 is a bottom plan view of the tray; and

FIG. 4 is a sectional view taken on line 4—4 of FIG. 1.

I claim:

The ornamental design for a packaging tray for a film reel, as shown.
